UNITED STATES PATENT OFFICE.

ALBERT B. LEE, OF MINNEAPOLIS, MINNESOTA.

GAGE FOR PARING-KNIVES.

1,346,321.

Specification of Letters Patent. Patented July 13, 1920.

Application filed March 14, 1919. Serial No. 282,690.

To all whom it may concern:

Be it known that I, ALBERT B. LEE, a citizen of the United States, residing in the city of Minneapolis, county of Hennepin, State of Minnesota, have invented new and useful Improvements in Gages for Paring-Knives, of which the following is a specification, reference being had to the accompanying drawings.

10 This invention relates to improvements in paring gages and more especially to a device adapted to be quickly adjusted to any ordinary paring knife for the purpose of facilitating the paring of potatoes and other 15 vegetables and fruits, and the object of my invention is to provide a device of this character which may be readily and quickly attached to any suitable paring knife and may be so adjusted to the cutting edge of the 20 blade thereof in such manner as to prevent the cutting away of too thick a peeling, and so as to reduce said peeling and the attendant waste as much as possible.

A further object is to provide such a device capable of such adjustment that either a thick or thin paring may be cut away as desired.

A still further object is to produce such a device in a very simple, practical and 30 economical form.

With these and other objects in view, attention is called to the drawings accompanying this specification, and constituting a part thereof, wherein—

85 Figure 1 represents a plan view of the gage as attached to the blade of a knife, and showing the extent to which the gage protrudes beyond the edge of the blade;

Fig. 2 is a detail perspective, showing the 40 method of attaching the gage to the blade of the knife;

Fig. 3 is a perspective showing the gage adjusted to the knife, and showing the combined apparatus in the act of paring a potato;

Fig. 4 is a frontal elevation of the gage as attached to the cutting edge of the knife blade.

Similar figures refer to similar parts 50 throughout the several views.

Referring more particularly to the drawings, Fig. 1 represents any ordinary paring knife as commonly used in and about a kitchen for the purpose of paring vegetables 55 and fruits; Fig. 2 represents my improved gage in its entirety; Fig. 3 represents a po-

tato in the process of being peeled; Fig. 4 represents the peeling as cut therefrom. In its preferable construction the invention is formed of a single piece of wire of a suitable 60 length and bent at its ends to form the coils 2 and 2' and embodying the connecting straight member or gage 3.

It will be noted that the coils formed at the ends of the gage 3 comprise a plurality of 65 loops though in actual construction perhaps not more than two loops would be embodied at each end. It will also be noted that the gage 3 is preferably thrown forward of the center of the coils 2 and 2'. The purpose of 70 a plurality of coils at each end of the gage is to facilitate the adjustment of the device for cutting to varying degrees of thickness, and the purpose of throwing the gage proper forward of the centers of the two sets of 75 coils is to aline the gage more conveniently adjacent to the cutting edge of the knife blade 1. The terminals of the coils are extended inwardly and are disposed diametrically of the end convolutions of the coils 80 and they fit against and frictionally engage the blade at points within the said coils and materially increase the effectiveness of the means for adjustably securing the device to a blade for retaining the device in its adjusted position.

In operation, the paring gage is set upon the cutting edge of any suitable paring knife by simply forcing the cutting edge of the knife blade 1 between the strands of the 85 coils 2 and 2' in such manner that the gage 3 becomes set and adjusted immediately over the cutting edge of the knife in such position that a small slit 5 is left between the cutting edge of the knife and the gage 3. 90 It is apparent that by adjusting the paring knife into and between the lower strands of the coils 2 and 2' the gage 3 would be relatively raised from the cutting edge of the knife blade 1, thereby increasing the thickness of the paring 4. When the gage 3 is 95 properly adjusted the paring process is proceeded with in ordinary form, the paring 4 passing upward through the slit 5, and it is obvious that this device enables the operator 100 to pare a vegetable evenly and smoothly and with great facility and speed, and the device as such can be attached to any suitable paring knife.

The drawings show the sets of coils 2 and 11 2' reversed in respect to one another, but the two coils may be disposed in identical rela-

tion to the gage 3; that is, turned in the same direction if so desired.

While I have herein shown certain specific manner and method of constructing my invention, it is understood I may vary from same in minor points, not departing from the spirit of my said invention so as best to construct a practical working device for the purpose intended.

10 What I claim to be new and patentable is:

1. A paring gage for knives comprising a straight gage member adapted to extend along the cutting edge of a knife in spaced relation with the same, terminal coils located 15 at the ends of the gage member adapted to embrace the blade of the knife, and extending terminals on said coils located within the

end convolutions and projecting inwardly and adapted to insure a tight frictional engagement with the knife blade.

2. In a device of the class described, including a knife, a straight gage member extending along the cutting edge of the knife in spaced relation with the same, terminal coils located at the ends of the gage member 25 and embracing the blade of the knife, and extending terminals arranged within and disposed diametrically of the terminal convolutions of the coils and fitting against and frictionally engaging the blade of said knife. 30

ALBERT B. LEE.
